US00D416236S

United States Patent [19]

Kobayashi et al.

[11] Patent Number: Des. 416,236

[45] Date of Patent: ** Nov. 9, 1999

[54] INTEGRATED CIRCUIT PACKAGE

[75] Inventors: **Kazuhiro Kobayashi**, Fujiyoshida;
Masayoshi Shiraishi; **Osamu Tanabe**,
both of Chiba, all of Japan

[73] Assignees: **Citizen Electronics Co., Ltd.**; **Seiko Instruments Inc.**, both of Japan

[**] Term: 14 Years

[21] Appl. No.: 29/093,046

[22] Filed: Sep. 2, 1998

[51] LOC (6) Cl. 13-03

[52] U.S. Cl. D13/182

CLAIM

The ornamental design for an integrated circuit package, as shown and described.

DESCRIPTION

FIG. 1 is a front elevational view of an integrated circuit package showing our new design;

FIG. 2 is a top plan view thereof;

FIG. 3 is a bottom plan view thereof;

FIG. 4 is a right elevational view thereof, the left side being the same in appearance as the right side;

FIG. 5 is a top, front, right perspective view thereof; and, FIG. 6 is a bottom, rear, right perspective view thereof.
